(57) **CLAIM**

The ornamental design for an air directing apparatus, as shown and described.

DESCRIPTION

FIG. 1 is a front-perspective view of an air directing apparatus, showing our new design;

FIG. 2 is a right-side view of the air directing apparatus, the left-side view being a mirror image of the right-side view;

FIG. 3 is a front-elevation view of the air directing apparatus;

FIG. 4 is a rear-elevation view of the air directing apparatus;

FIG. 5 is a top-plan view of the air directing apparatus, the bottom-plan view being a mirror image of the top-plan view;

FIG. 6 is a rear-perspective view of the air directing apparatus;

FIG. 7 is a tilted front-perspective view of the air directing apparatus;

FIG. 8 is a titled rear-perspective view of the air directing apparatus; and,

FIG. 9 is an exploded view of the air directing apparatus.

The broken line showing of parts of the drawings is included for the purpose of illustrating use and environment and forms no part of the claimed design.
